CIGARETTE

James C. Seney, Lawrence, Mass., assignor of one-fourth to James J. Sullivan, Andover, Mass., and three-eighths to George M. Austin, Lawrence, Mass.

Application March 28, 1940, Serial No. 326,376

6 Claims. (Cl. 131—4)

My present invention relates to cigarettes, and more particularly to an improved cigarette having a fire-stop member located inside the cigarette.

It is a well known fact that cigarettes are great fire hazards. Thousands of fires are started every year from cigarette butts thrown down while in a lighted condition.

Frequently automobilists throw lighted cigarette butts from moving automobiles onto the roadsides and thereby cause serious and costly forest fires. Other forest fires are caused from people dropping lighted cigarettes on the ground. Numerous household furnishings become damaged when lighted cigarettes are left too long, as on the edge of a table, etc.

In my present invention, I have produced a cigarette with a fire-stop member located inside of the cigarette adjacent one end at approximately the distance from the mouth end where most cigarette smokers throw away the cigarette. When the cigarette burns up to this fire-stop member, the cigarette automatically goes out.

The principal object of my invention therefore, is an improved cigarette;

Another object is a cigarette which will automatically become extinguished at a predetermined point, and

Other objects and novel features comprising the construction and operation of my device will be apparent as the description of the same progresses.

In the drawing illustrating the preferred embodiment of my invention;

Fig. 1 is a perspective view of the cigarette, the scale being exaggerated;

Fig. 2 is another exaggerated perspective view of my improved cigarette, one end of the cigarette casing being split open for a portion of its length to show the relationship between the tobacco and the fire-stop member, and

Fig. 3 is a greatly exaggerated cross-section taken on the line 3—3 of Fig. 1 showing the mouth end of the cigarette and inclosed fire-stop member in cross-section in greater detail.

Referring more in detail to the drawing, 10 indicates the casing of a cigarette. As is well known such casings are made from special paper.

At 11 and 12 I have shown a packing of cigarette tobacco, the two packings 11 and 12 being divided by a pellet 13. This pellet 13 is preferably impervious to smoke and composed of a core 14 composed of some suitable fire resisting material, as asbestos or the like and which is surrounded with a covering of tin-foil 15. Other

core material such as cork etc. may be used, or I may make the entire pellet of tin-foil. The shape of the pellet 13 may be rectangular, as shown.

In the drawing, I have shown tobacco at 11 but 5 any other material may be used on the mouth end if desired. In the use of tobacco on the mouth end the appearance of the cigarette is identical with any conventional brand.

It will be noted that the tin-foil covering 15 is 10 provided with a rough or crinkled surface, as shown in Fig. 3 and indicated in Fig. 2. This irregular surface provided on the pellet provides a smoke passage 16 between the pellet 13 and the inside surface of the casing 10.

15 In operation, the cigarette is lighted and smoked in the same manner as any conventional cigarette but when the tobacco 12 has been burned up to the face of the pellet 13 the cigarette becomes extinguished automatically. The 20 extinguishing of the cigarette takes place whether or not the cigarette is being smoked at the time. If the cigarette has been left on an ash tray or on the edge of a table or other piece of furniture no damage occurs.

25 It will thus be seen that I have invented a safety cigarette of great usefulness and while I may change the shape and proportions of the pellet or its position in the cigarette casing it is to be understood that such variations are within 30 my rights and in keeping with the spirit of the invention.

Having thus described my invention, what I claim as new is:

1. An improved cigarette comprising in combination, an outer casing, a fire resisting member located inside said casing, said fire resisting member comprising a pellet having an outer shell composed of tin-foil and a core of fire resisting material, said pellet being located in said casing adjacent one end of said cigarette, and cigarette tobacco located in said casing at either end of said pellet.

2. In an improved cigarette having an outer combustible casing and combustible tobacco located within said casing, a tin-foil covered pellet located inside of said casing adjacent one end of said cigarette, the said tobacco being separated by said pellet.

3. An improved cigarette having an outer casing and tobacco located within said casing, a tin-foil covered fire-resisting fire-stop member located inside said casing adjacent one end thereof, and a smoke passage located between said casing and said fire-stop member.

55 4. An improved cigarette comprising in combi-

nation, an outer casing, a pellet located inside said casing, said pellet having a fire resisting core covered with tin-foil, the said tin-foil having an irregular surface contacting the inner surface of said casing, smoke passages comprising said irregularities located between said tin-foil and the inner surface of said casing, and tobacco located inside of said casing and contacting with one end of said pellet.

5. In a cigarette having an outer casing and an inner packing of tobacco, a fire-stop member located in said casing adjacent one end of said cigarette, said fire-stop member having a tin foil irregular crinkled surface, and a smoke passage

10 between said fire-stop member and the inner surface of said casing, said passage being formed by means of the irregularities comprising the crinkled surface of said tin-foil.

6. An improved cigarette, said cigarette having an outer casing, a fire-stop member impervious to smoke located in said casing and contacting the inner side of said casing, the said fire-stop member having an outer irregular surface forming irregular smoke passages, and tobacco located adjacent both ends of said fire-stop, said fire-stop member having substantially the same cross-sectional area as that of the tobacco.

JAMES C. SENAY.
